HERMAN WILLIAMS, OF HOMESTEAD, PENNSYLVANIA.

MANUFACTURE OF BILGED METALLIC BARREL-BODIES.

1,259,573.

Specification of Letters Patent. Patented Mar. 19, 1918.

Application filed January 22, 1916. Serial No. 78,705.

To all whom it may concern:

Be it known that I, HERMAN WILLIAMS, a citizen of the United States, and resident of Homestead, in the county of Allegheny and

5 State of Pennsylvania, have invented certain new and useful Improvements in the Manufacture of Bilged Metallic Barrel-Bodies, of which the following is a specification.

This invention relates to the manufacture 10 of bilged barrel bodies from metal plates of suitable gage, and the primary object is to so displace the metal incident to forming the bilge as to distribute it uniformly throughout the bilged portion and avoid the buckling or crimping tendency commonly experienced, particularly at or adjacent the marginal portions of the sheet. The new method herein involves a manipulation 15 wherein all portions of the sheet or plate are placed under tension during the forming operation, there being no opportunity for the creation of compression strains which are immediately responsible for the appearance 20 of crimps or laps in the bilged bodies.

25 It is further characteristic of the invention that in forming the bilge the metal is displaced in a direction transversely of the sheet, *i. e.*, longitudinally of the barrel body, there being a relatively small amount of displacement lengthwise of the sheet. By this means the stretching and consequent thinning of the metal is distributed uniformly throughout the sheet, with all portions thereof of substantially uniform strength.

35 In the preferred practice, the flat plate is curved to fit within the curved marginal portion of a bed or press, the bed intermediate its marginal portions being depressed in conformity with the bilge to be imparted 40 to the plate. After tightly securing the margins of the positioned plate so that there can be no slipping or bodily displacement in any direction, a portion of the plate, preferably a part located intermediate its ends, is 45 pressed into the bilge-forming cavity of the body by means of a former or die element which conforms to such depression. This result is produced primarily by stretching the metal transversely of the plate, and the 50 portion thus shaped is securely held or clamped by the forming element, thereby placing and maintaining all of the remainder of the plate under tension. Such remaining portions are then pressed into full 55 conformity with the bed depression, and with the metal under tension and with no

opportunity for compression strains to develop, the result is a uniformly bilged plate from which kinks or laps are totally absent. The bilging operation which follows initial 60 pressing of the blank is preferably accomplished by the combined pressing and rolling action of die-like formers having faces shaped complementary with the bed depression, such forming operation proceeding 65 progressively from the initially pressed portion to the ends of the blank by a rolling or ironing-out action which expands the sheet principally in the direction of its width or longitudinally of the length of the 70 barrel body, thereby eliminating such plate deformations as may result during the initial pressing from placing the metal under tension, and completing the bilging operation. 75

Apparatus for practising the invention is illustrated in the accompanying drawings, Figure 1 being a side elevation of a desirable adaptation thereof. Fig. 2 is a vertical cross-section on line 2—2 of Fig. 1. Fig. 3 80 is a sectional plan on line 3—3 of Fig. 1. Fig. 4 is a bottom plan view of the die elements which coöperate with the recessed base of the press. Fig. 5 is a central vertical section of the press, the central die element 85 being shown depressed for accomplishing the preliminary pressing of the plate, and Figs. 6 and 7 illustrate the blank at the completion of the preliminary pressing operation. Fig. 8 is a view similar to Fig. 5 showing 90 the die elements fully expanded as at the completion of the bilge-forming operation, and Figs. 9 and 10 are detail views of the fully bilged blank. Fig. 11 is a view of the bilged blank after it has been rolled or 95 curled into body form.

Referring to the drawings, 2 designates the bed or base portion of the press, the top surface thereof formed with the downwardly curved depression 3, and this depression 100 within its marginal portions is dished or recessed at 4 in conformity with the curvature of the bilge to be imparted to the plate or sheet A. This sheet is curved to fit within depression 3, with its marginal side portions *a* resting on the curved margins of depression 3, and with the ends *b* of the blank bearing downwardly on top of base 2 at opposite ends of depression 3. If desired, bed 2 may be in the form of a magnet for 110 retaining the plate in proper position preceding the securing of the plate margins.

For confining the plate on the bed, a vertically movable frame is employed which is provided with the depending side portions 5 curved complementary with depression 3 and the transverse end portions 6 adapted to bear downwardly on the bed at opposite sides of depression 3. The curved side portions 5 engage the longitudinal margins *a* of the blank A, while the cross elements 6 similarly engage end flanges *b* thereof, so that when the frame is forced into position as by compressed air cylinder 7 which may be operatively connected to the frame ends 6, the plate is securely clamped and held at all marginal portions, and displacement in any direction under the strains incident to the bilge-forming operation is rendered impossible. Cylinders 7 may be conveniently supported by posts 8, the latter being embraced at 9 by the clamping frame and constituting guides therefor. The upper ends of the post may be connected by beams 10.

In the arrangement shown, the die elements which are movable vertically through the open clamping frame and which co-operate with the bilged base 2, consist of a rail-like relatively narrow die part 11, to the opposite sides of which are hinged at 12 the expandable die elements 13. Die 11 is secured to the lower end of frame 14 which terminates in piston rod 15 and piston 16 of a cylinder 17, the latter being supported by beams 10. With compressed air connections leading to opposite ends of the cylinder from main 18 and controlled by valve 19, die element 11 may be lowered and raised at the desired intervals. Dies 13 are adapted to be rocked on their hinges 12 simultaneously by means of links 20 connected to piston rod 21 and piston 22 of a cylinder 23, the latter being embodied in frame 14 and hence movable vertically when die 11 is operated without, however, operating the die parts 13 other than to raise and lower them. With flexible compressed air connections extending to opposite ends of cylinder 23 and in controlled communication with main 18 by valve 24 the parts 13 may be rocked as required to complete the bilging operation.

The under faces of the die parts 11 and 13 are curved complementary with the bilge-forming depression 4 of base 2, and hence when die 11 is depressed as indicated in Fig. 5, a portion of the blank is given its ultimate form, and as the entire blank is marginally so held as to prevent slipping or displacement, the remainder of the plate is placed under tension somewhat as indicated in Figs. 5, 6 and 7, such tension resulting in the development of wave-like irregularities *c* at opposite sides of the central portion *d* shaped by former 11. With the intermediate portion of the plate shaped and securely held by die 11, and with the

remainder of the marginally clamped plate under tension (there being a total absence of compression strains) the metal is given the bilge formation by the action of die parts 13. The latter swing on their hinges 12 and rock outwardly progressively from the hinge joints as links 20 lower from the position shown in Fig. 5 to that of Fig. 8, thereby progressively stretching or expanding the metal into depression 4 as by a rolling, ironing-out action which terminates at the margins *b* upon fully lowering dies 13, thereby completing the bilging operation.

The action of dies 13 is substantially the same as die 11 in stretching or expanding the metal primarily in direction across the sheet or longitudinally of the bilged body. This is an important and advantageous difference over the usual procedure wherein the expansion is produced primarily by stretching the sheet in the direction of its length which results in so distorting the metal as to set up compression strains in the sheet principally adjacent its margins, and such strains develop kinks and laps which cannot be removed. With the necessary increase in peripheral length produced by a transverse stretching that proceeds progressively from an initial similarly stretched portion of the plate, there is very little immediate stretching longitudinally of the plate in a longitudinal direction, although such transverse stretching results in producing the increase in peripheral length necessary to produce the bilge.

Hinges 12 are arranged as close as is practicable to the under face of the die parts, and are preferably of knuckle or joint form as shown. The connected parts are preferably formed with the interfitting projections and depressions illustrated in Fig. 4 which so hold the metal at the joint lines during the rolling or ironing-out process as to avoid the formation of folds or kinks.

When the operation proceeds as described, the metal under tension is so displaced and distributed as to provide a bilged body of substantially uniform thickness, save at its confined marginal portions, and the procedure throughout is marked by a total absence of kinks or laps. Upon withdrawing the die elements and relaxing the hold of the clamping frame, the bilged plate may be removed and its margins trimmed as required to form the barrel body shown in Fig. 11, the bilged blank being curled into circular form by any of the means well known in the art. Flanges *a*, or portions thereof may be retained to provide chines for the barrel body.

I claim:

1. The method of producing bilged barrel bodies which consists in curving a flat sheet to fit within the marginal portions of a bed or press, which intermediate said portions

- is depressed in conformity with the bilge to be imparted to the sheet, then immovably holding the longitudinal edges of the sheet and progressively bilging the sheet from at 5 or near its center outwardly to the opposite ends thereof.
2. A method of producing bilged barrel bodies consisting in confining a metal sheet to prevent contraction thereof, and stretching the sheet in the direction of its width or longitudinally of the ultimate barrel body with such stretching proceeding progressively throughout the length of the sheet.
3. A method of producing bilged barrel bodies consisting in confining the marginal portions of a metal sheet to prevent contraction, and stretching the sheet in direction longitudinally of the ultimate barrel body with such stretching imparted initially to a 10 portion of the sheet and proceeding progressively from such initial portion throughout the length of the sheet.
4. A method of producing bilged barrel bodies consisting in confining the marginal portions of a metal sheet to prevent contraction, subjecting a portion of the sheet to bilge-forming pressure in a direction longitudinally of the ultimate barrel body and thereby placing under tension the remainder 15 of the sheet, and bilging such remainder by pressure applied subsequently to said initial bilging.
5. A method of producing bilged barrel bodies consisting in confining the marginal portions of a metal sheet to prevent contraction, subjecting a portion of the sheet to bilge-forming pressure in a direction longitudinally of the ultimate barrel body and thereby placing under tension a portion of 20 the sheet between such bilged portion and the confined blank margins, and bilging the remainder of the sheet by a progressive rolling action proceeding from said bilged portion to the extremity of the blank distant 25 therefrom.
6. A method of producing bilged barrel bodies consisting in curving a flat sheet of metal in the direction of its length, confining the curved sheet at all of its margins and thereby forestalling contraction, exerting bilge-forming pressure on a portion of the sheet in direction longitudinally of the ultimate barrel body and thereby placing the remainder of the marginally held sheet 30 under tension, and deforming such remain- 35 der by a rolling bilge-forming pressure proceeding progressively from said initially bilged portion to the confined margin of the sheet distant therefrom.
7. A method of producing bilged barrel bodies consisting in placing a sheet of metal on a form that is curved longitudinally of the sheet and bilged transversely thereof, confining the marginal portions of the sheet against contraction in any direction, placing a transversely extending portion of the sheet under deforming pressure and thereby conforming said portion to the bilged form with such deformation placing the remainder of the sheet under tension, and forcing the portion of the sheet under tension into engagement with the bilged form by pressure proceeding progressively from said initially bilged portion to the margin of the sheet distant therefrom.
8. A method of producing bilged barrel bodies consisting in placing a sheet of metal on a form that is curved longitudinally of the sheet and bilged transversely thereof, confining the marginal portions of the sheet against contraction in any direction, placing a portion of the sheet located intermediate its ends under deforming pressure and thereby conforming said portion to the bilged form with such deformation placing the portions of the sheet at opposite sides thereof under tension, and forcing such portions under tension into engagement with the bilged form by pressure proceeding progressively and in opposite directions from said initially bilged portion to the confined sheet ends.
9. The method of producing bilged barrel bodies which consists in semi-cylindrically curving a metal sheet and forming thereon projecting end flanges, in placing such curved sheet over a bilged form or die and holding its marginal edges against displacement, then forcing said sheet into the die so as to initially bilge it at or near its mid position between said flanges, then bilging the remainder of the sheet from said initially bilged portion in a progressive manner to said end flanges.
